UNITED STATES PATENT OFFICE.

ISAAC L. EDWARDS, OF AURORA, ILLINOIS.

DESIGN FOR A RAILROAD-TIE PLATE.

52,159.

Specification for Design.

Patented July 9, 1918.

Application filed April 20, 1917. Serial No. 163,534. Term of patent 14 years.

To all whom it may concern:

Be it known that I, ISAAC L. EDWARDS, a citizen of the United States, residing at Aurora, in the county of Kane and State of Illinois, have invented a new, original, and ornamental Design for Railroad-Tie Plates, of which the following is a specification, reference being had to the accompanying drawing, forming part thereof.

The figure in the drawing is a perspective view of a tie plate for application to the tie of railroads and engagement of the rail, reference to which drawing will show that it

comprises a flat base and arms which arch upwardly from the top of the base and extend toward each other, there being a pair of such arms on one side and one on the other situated substantially midway between the pair so that the free rail web-engaging end of one arm is turned toward or faces the similar ends of the pair of arms, and such ends are ridged, or corrugated.

I claim—

The ornamental design for a railroad tie plate as shown and described.

ISAAC L. EDWARDS.
